(No Model.)

I. C. BEATTY.

LOOM.

No. 465,515.

Patented Dec. 22, 1891.

FIG. 1

UNITED STATES PATENT OFFICE.

IRVINE C. BEATTY, OF MERCHANTVILLE, NEW JERSEY.

LOOM.

SPECIFICATION forming part of Letters Patent No. 465,515, dated December 22, 1891.

Application filed July 31, 1890. Serial No. 360,433. (No model.)

To all whom it may concern:

Be it known that I, IRVINE C. BEATTY, of Merchantville, Camden county, New Jersey, have invented an Improvement in Looms, of which the following is a specification.

My invention has reference to looms; and it consists of certain improvements, all of which are fully set forth in the following specification, and shown in the accompanying drawings, which form a part thereof.

My improvements particularly relate to that class of looms in which a number of heddles are employed and a series of sets of warp-threads are required in the production of the fabric.

A part of my invention relates to improvements in the letting-off or tension device for the warps.

The particular construction of my letting-off or tension device for these various warp-threads is fully described hereinafter when referring to the drawings.

A second part of my invention consists in devices for bringing the various warps from

the heddles in separate layers over the top of the loom and by suitable guide-rods or rollers to the tension or letting-off devices and locating such tension or letting-off devices in the front or back of the loom, but separated

from it sufficiently to enable the operator to pass between the loom proper and the upwardly-extending warp-threads and their tension or letting-off devices. This enables the operator to watch the weaving of the various

webs and at the same time by simply turning his head to have in full view every warp-thread which is being fed to the loom, thereby being enabled to observe and in position to overcome any defect which might exist by the

breaking of a warp-thread long before the end of said broken warp-thread passes through the heddle.

While my invention is particularly adapted to looms for weaving a series of separate webs

when all are controlled from the same power mechanism, it is also applicable to any type of loom in which two or more sets of heddles are employed.

In the drawings, Figure 1 is a sectional elevation of a loom and the tension or letting-off devices embodying my invention. Fig. 2 is a perspective view of one of the letting-off or

tension devices. Fig. 3 is a front view showing two of the guide-rollers of a pair of tension devices, illustrating how the weights of the upper roller may pass below the level of the lower tension-roller; and Fig. 4 is a perspective view of one of the brake-frames for carrying the tension-roller and guide-roller, showing the use of vertical guides for the tension-roller.

A represents the loom proper, which is provided with the usual reed and lathe and the heddles B, of which there may be any desired number. To the rear of the heddles are arranged a series of bars, guides, or rods C, preferably one for each series of warps. Arranged to the upper part of the loom over the rods C are a similar series of rods or guides D, and again in front of the machine and above where the operator would pass in attending the loom is a third series of such bars or guides E. The bars or guides D and E are arranged obliquely, so as to keep the various layers of warp-threads separated as far as practicable.

In the front of the machine is arranged the tension or letting-off devices F, which are located one above the other and so positioned with respect to the loom proper that a passage-way P is formed for the operator, whereby he may either attend the loom A or examine the various warps passing over the spools of the tension or letting-off devices. If the tension devices are located in the front of the loom, then the passage-way P is arranged between the lathe portion of the loom and the tension devices, while if the tension devices are arranged at the back of the loom the passage-way P would be arranged between the heddles and the tension devices. In either case there is a passage-way upon both sides of which are vertical layers of warp and overhead horizontal or substantially horizontal layers of warp, each layer separated sufficiently to permit easy inspection and repair of the warp. Furthermore, in either case the passage-way is between the tension devices and the loom proper and permits the ready inspection, adjustment, and repair of each.

The tension devices are clearly shown in Fig. 2 and consist of the following elements: a bobbin or spool G, journaled in an upright frame H and carrying the warps for one of

the heddles, and a frame I, pivoted below said spool at J, in which is journaled or supported a roller or guide-rod L. Tension-cords K pass around the flanges g of the spool G, one end 5 of which cords is fixed to the frame H by being connected to the pivot J, and the other end of which cord is connected to the frame I at a distance from its pivot or fulcrum point J. It will be seen that any tendency to press 10 down the free end of the frame I will cause a tension to be exerted by the cords or bands K upon the spool or bobbin G and prevent its unwinding, and vice versa. The warp-threads pass from the spool G over the guide 15 rod or roller L and under a roller or guide M, which is weighted at each end by weights N. From under said roller or guide M the said warps pass upward to the guide-rods E, thence to guide-rods D, thence downward under the 20 guide-rods C to the heddles. The axles of the guide-rollers M may be guided in vertical guides i on the frame I, said guides being clearly shown in Fig. 4. Such guides prevent any lateral swaying of the guide-roller. However, if desired, these guides 25 may be dispensed with. As the loom takes up the warp-threads the guide rod or roller M is lifted until it lifts the frame I, releasing the tension on the spool G, which action allows 30 the weighted roller or guide M to pull down gradually, causing the spool G to let off a certain amount of the warp-threads. As soon as the roller or guide M falls the downward pressure of the warp-threads on 35 the roller L forces down the frame I and arrests further movement of the spool G. During the further action of the loom the warp which is taken up in the manufacture of the fabric draws upon that portion of the 40 warp in which the roller or guide M is suspended and gradually lifts said roller or guide M and its weights N until it again lifts the frame I and repeats the operation of letting off the given amount of warp, as before. 45 There is a series of these tension and letting-off devices arranged one above the other in the frame F, as indicated in Fig. 1, and the guide rods or rollers E are arranged slightly at an angle to the loom, so that the various 50 layers of warp-threads rise upwardly and at a slight angle in order that each set of warp-threads may be kept separate from the various tension devices, and thereby not interfere with the tension on any other set of warp-threads. 55 All of the brake-frames I may be of the same size or they may be of varying sizes, increasing from top to bottom; but in this latter case the increasing leverage of the frame 60 I would be compensated for by a decrease in the brake power caused by removing the connection of the brake-band farther from the fulcrum-point J. A convenient method is to make these frames I of the same size in 65 pairs—that is to say, the two highest being of the same size, the next two larger, but of the same size, and so on—thus enabling the

rollers L and M to be carried farther out to insure a more ready guidance of the warp to the guide-rods E and a clearance of the tension-weights. This difference in the size of the frames I is clearly shown in dotted lines in Fig. 1. Where the vertical space is limited for any given number of spools G, it is desirable to make the axle of the upper tension- 70 roller M of a pair longer, so that the weights N, suspended therefrom, may descend outside of the weights N of the roller M immediately below, as is shown in Fig. 3. The weight N of the next pair above being located nearer 80 to the spool G, they could descend without coming into contact with the weights below. By this construction a maximum vertical movement of the roller M may be had with the limited vertical space in which the spools 85 G are located.

By my improvement I am enabled to feed the various threads in flat layers, so that there is no tendency whatever for tangling or knotting of the various threads making up 90 the fabric, and each and every thread can be readily observed by the operator at all times, thus overcoming any complication which might result from defects in the threads when fed to the loom in rope-like layers, as has 95 been customary heretofore.

The construction of the loom may be such as is heretofore well known, and may be varied to suit the requirements of the manufacture of any special kind of fabric. Consequently I 100 do not limit myself to the details thereof. Likewise the details of my improved tension device may be modified without departing from the spirit of the invention, and I might add that, broadly considered, it is immaterial 105 where the said tension device is located with respect to the loom; but I prefer to locate it as shown, so as to form the passage-way for the operator between the spools the loom proper. 110

Having now described my invention, what I claim as new, and desire to secure by Letters Patent, is—

1. The combination of a loom proper, a series of independent tension and letting-off devices arranged one above the other at a distance from the loom sufficient to form a passage-way for an operator to stand and inspect, adjust, or repair the loom or tension and letting-off devices or warp-threads, and guides 115 for guiding the warp-threads from the tension and letting-off devices in a vertical and horizontal direction about the passage-way without obstructing it, so that they may be maintained in layers for easy inspection and 120 repair.

2. The combination of a loom with a tension and letting-off device located at the front of the loom and sufficiently removed to form a passage-way for the operator between the 130 loom and said tension or letting-off device, and in which the latter consists of a spool for the warp-threads, a pivoted frame, a brake-band passing about said spool and op-

erated by the frame to hold or release the spool, a guide for the warp-threads passing from the spool carried by said pivoted frame, a weighted guide or tension device acting upon the warp-threads beyond the guide of the pivoted frame, and suitable guides arranged above the machine for leading the warp-threads from the tension-guide to the heddle of the loom.

10. 3: The combination of a loom proper having a series of heddles, a series of separate spools for containing the warp-threads for the respective heddles and located in the front of the loom and so as to form a passage-way between the loom proper and said spools, whereby the operator may readily observe all of the warp-threads and the action of the loom in weaving, and suitable guides for leading said warp-threads passing from the several 15 spools to the rear of the loom proper and to the respective heddles.

4. The combination of a loom proper having a series of heddles, a series of separate spools for containing the warp-threads for the 20 respective heddles, located in the front of the loom and so as to form a passage-way between the loom proper and said spools, whereby the operator may readily observe all of the warp-threads and the action of the loom in weaving, suitable guides for leading the said warp-threads from the several spools to the rear of the loom proper and to the respective heddles, and automatic tension devices, substantially as set forth, for each of the spools for 25 controlling the supply and tension of the warp-threads which are delivered to the loom.

5. The combination of a loom proper having a series of heddles, a series of separate spools for containing the warp-threads for the 30 respective heddles, located in the front of the loom and so as to form a passage-way between the loom proper and said spools, whereby the operator may readily observe all of the warp-threads and the action of the loom in weaving, suitable guides for leading said warp-threads from the several spools to the rear of the loom proper and to the respective heddles, and automatic tension devices for each 35 spool to control the feeding of the warp-threads, consisting of a pivoted frame I, a brake-band K, passing about the spool and actuated by said frame I, a guide or roller L for the warps carried by said frame I, and a weighted roller or guide M, around which 40 the warps pass before being delivered to the heddles.

6. The combination of a loom proper having a series of heddles, a series of separate spools for containing the warp-threads for the 45 respective heddles, arranged one above the other and located at a distance from the loom sufficient to form a passage-way for the operator, whereby he may readily observe the warp-threads and action of the loom during 50 weaving, and suitable guides for guiding the warp-threads passing from the several spools to the rear of the loom in layers about said

passage-way, whereby the operator while standing in the passage-way may inspect and repair said warp-threads.

7. The combination of a loom proper having a series of heddles, a series of separate spools for containing the warp-threads for the respective heddles, arranged one above the other and located at a distance from the loom 75 sufficient to form a passage-way for the operator, whereby he may readily observe the warp-threads and action of the loom during weaving, suitable independent guides for guiding the warp-threads passing from each 80 of the several spools to the rear of the loom in separate parallel layers about said passage-way, whereby the operator while standing in the passage-way may inspect and repair said warp-threads, and independent tension and letting-off devices for each spool. 85

8. The combination of a loom proper having a series of heddles, a series of separate spools for containing the warp-threads for the respective heddles, arranged one above the other 90 at a distance from the loom to form a passage-way, a series of brake-frames and brake-applying devices actuated thereby for arresting the rotation of the respective spools, also arranged one above the other, a fixed guide 95 on each of the brake-frames, over which the warp-threads pass, a movable weighted guide for each of the brake-frames, under which the warp-threads pass before being led to the heddles of the loom, the adjacent brake-frames 100 being of different lengths, so that the movable guide and its weights shall be located to one side of the vertical plane of the guide and the weight of the brake-frame immediately below, and guides for the warp-threads 105 of the respective spools for leading the threads around the passage-way in open sheds or layers.

9. The combination of a loom proper having a series of heddles, a series of separate spools for containing the warp-threads for the respective heddles, a series of brake-frames and brake-applying devices actuated thereby 110 for arresting the rotation of the respective spools, a fixed guide on each of the brake-frames, over which the warp-threads pass, and a movable weighted guide for each of the brake-frames, under which the warp-threads pass before being led to the heddles 115 of the loom, the upper movable guide having 120 its weights supported at a greater distance apart than the weights of the movable guide immediately below, whereby said weights of the upper movable guide may pass the movable guide and weights immediately below. 125

10. The combination of a loom proper having a series of heddles, a series of tension devices arranged in pairs, each of which consists of a spool, a brake-frame, a brake-applying device actuated by said frame, a guide 130 upon said brake-frame, over which the warps pass, and a movable weighted guide located under said brake-frame and under which the warps pass, the brake-frames of the pairs of

- tension devices increasing in length from top to bottom in the series and the weights of the upper movable guide of each pair of tension devices being arranged farther apart than the weights of the lower movable guides of the corresponding pair, whereby said upper weights may pass the lower weights, the whole being constructed to give a maximum given feeding capacity with a limited vertical height.
11. The combination of a loom proper, a tension and letting-off device for warp-threads, arranged at a distance from the loom sufficient to form a passage-way and permit an operator to pass between it and the loom proper, and guides for guiding the warp-threads

from the tension and letting-off device in a vertical and horizontal direction about the passage-way without obstructing it and maintaining the said warp-threads in a layer for easy inspection and repair, the construction being such that the operator may readily inspect, adjust, or repair the loom or tension and letting-off device or warp-threads without materially shifting his position.

In testimony of which invention I have hereunto set my hand.
